H. T. BLACKWELL,
TRIMMING MACHINE.
APPLICATION FILED MAY 28, 1917.

1,286,889.

Patented Dec. 3, 1918.

INVENTOR.
Harry T. Blackwell
By his Attorney,
Nelson W. Weston.

UNITED STATES PATENT OFFICE.

HARRY T. BLACKWELL, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TRIMMING-MACHINE.

1,286,889.

Specification of Letters Patent.

Patented Dec. 3, 1918.

Application filed May 28, 1917. Serial No. 171,447.

To all whom it may concern:

Be it known that I, HARRY T. BLACKWELL, a citizen of the United States, residing at Brockton, in the county of Plymouth and 5 State of Massachusetts, have invented certain Improvements in Trimming-Machines, of which the following description, in connection with the accompanying drawings, is 10 a specification, like reference characters on the drawings indicating like parts in the several figures.

This invention relates to rotary trimming machines, and in particular to machines used to trim the edges of the soles of shoes.

15 The cutters used in these machines are rotated at very high speed, for example, 7300 R. P. M. It is necessary that parts rotating at such speed be very accurately balanced in order to avoid vibration, and this is especially necessary in a sole edge trimming machine since these machines have been found to be exceedingly sensitive to vibration, which causes a wavy effect to appear in the 20 trimming.

25 The operator presents the shoe to the cutter with his fingers along the sole, near the edge, in order to steady it properly, and moves the sole edge over the cutter. It is necessary to protect his finger from the ends 30 of the cutter teeth and this is done by a "sleeve" which encircles the shaft, fits up against the base of the cutter and is of slightly larger diameter than the base of the cutter. The operator may rest his finger 35 against this sleeve with safety.

It has been a custom in the past to mount this sleeve on the rotating shaft, which it was very likely to throw out of balance, and the balancing of the sleeve and shaft to permit rotation without vibration at the high speed mentioned, was a very troublesome matter. It was also necessary to make the sleeve adjustable longitudinally of the shaft in order to adapt it to use with cutters of 40 different thicknesses, and the construction required in order to obtain this advantage aggravated the problem of balancing.

A further difficulty is met with in these machines, which prejudices the accuracy of

the operation they perform. It has been 50 found impossible to manufacture the cutter itself in the first instance so that it will balance and run with all its cutting edges on a circle around the center of rotation. Any 55 lack of concentricity of the totality of the cutting edges about the rotational axis will cause trouble. A good trimmer can detect a deviation from true running amounting to considerably less than 0.001 inch. The hardening of the cutter generally warps it 60 slightly and besides, the shaft on which it is placed may be a little out of balance. When the shaft and cutter are rotated at high speeds such as the speed mentioned, the system will tend to balance itself about its own 65 center of gravity, but the cutter, even if perfect in itself, will not run true.

It is necessary then to true the cutter after it has been mounted in the machine, and with reference to its running position and 70 preferably at the speed at which it is to be actually run. This is done by supporting, in some manner, a piece of steel, such as a screwdriver blade, or a piece of corundum or carborundum, close to the rotating cutter, 75 and holding it so that the "high" teeth will be nicked by it as they rotate, and then grinding back the front faces of the nicked teeth to the bottoms of the nicks. It is of course necessary that the object used to 80 nick the teeth be held with the greatest care and steadiness.

It is the object of my invention to provide a simple and cheaply manufactured means of dealing with the above described problems, and to make the machine convenient and easy to handle. I accomplish this by providing a rest for the truing tool in convenient position to be used in the truing operation. In the embodiment shown in the 90 drawings I have united the finger guard and tool rest in one element, thereby providing an additional steady rest for the hand during the truing operation. This element is shown adjustable so that the rest may be 95 put in the most advantageous working position and may be moved out of the way when no longer needed, keeping the guard in its

normal relation to the cutter, for use in the trimming operation.

These and other features of the invention comprising various combinations and arrangements of parts will be best understood and appreciated from the following description of a preferred embodiment thereof selected for purposes of illustration and shown in the accompanying drawings in 10 which,

Figure 1 is a side elevation of the machine,

Fig. 2 is a perspective of the sleeve, shaft, and cutter, and

15 Fig. 3 shows the procedure used in truing the cutter.

The cutter shaft 10 is rotated in bearings in the head 12 by the pulley 14. A cylinder 16 is mounted on a strap 18 which is fastened to the head by an oil cup 20, screwing through a hole in its end. The cylinder is supported substantially concentric with the shaft 10, on the projecting end of which the cutter 22 is mounted, the shaft being of considerably less diameter than the inside of the cylinder.

The cylinder carries the sleeve 24, which is slideable longitudinally and tangentially in the cylinder and on the shaft, and is 30 clamped in adjusted position by a screw 26. It is therefore normally stationary relative to the shaft, and the shaft balancing problem is not affected by its presence or adjustment.

35 The outer end of the sleeve is flanged, a part of the flange, 28, being of slightly greater radius than the ends of the teeth at the base of the cutter. The remainder of the flange 30, is shown of greater radius, and 40 carries a projection 32, parallel to the shaft and of length about equal to the height of the cutter. When the cutter has been securely mounted on the shaft, the screw 26 is loosened, the sleeve 24 is turned over into the

45 position shown in Fig. 3 and fastened there by the screw, and the machine is started and run up to speed. The broadened flange 30 is then under the cutter and the projection 32 is in position to act as a rest for the truing tool 34. This tool is held by the operator, 50 who may rest his finger on the flange 30 to steady his hand, and is carefully advanced until the high teeth strike the tool in their rapid rotation. The machine is then stopped 55 and these teeth are ground down to the bottoms of the nicks. The cutter will then be true when the shaft is running. When the truing of the cutter has been finished the sleeve is turned up to the position of Fig. 1

60 and the narrower portion 28 of the flange will serve as a guard for the operator's finger in the normal use of the machine. The grinding of the cutter will be done preferably in a machine adapted for that operation, the

cutter being removed from the trimming machine for that purpose. It is of course necessary that the cutter be replaced on the trimming machine shaft in exactly the same relative position it occupied when it was nicked, in order not to vitiate the result of 70 the trimming operation.

I have thus provided a sleeve which fulfills all the requirements of the sleeve heretofore used, which will not throw the shaft out of balance and which will serve as a 75 guard and a steady rest during the truing operation.

Having described the invention, what I claim as new and desire to secure by Letters Patent of the United States is:

1. In a machine of the class described, a cutter carrying shaft adapted for high-speed rotation, and a sleeve surrounding the shaft carrying a guard constructed and arranged to prevent the operator's hand from coming 85 into contact with a side of the cutter, while leaving substantially the entire periphery of the cutter exposed, said sleeve carrying also a rest for a truing tool which extends substantially across the face of the cutter. 90

2. In a machine of the class described, a shaft carrying a cutter, and a stationary member adjustable relative to the cutter, carrying a guard constructed and arranged to prevent the operator's hand from coming 95 into contact with a side of the cutter while leaving substantially the entire periphery of the cutter exposed, and a rest extending across the width of the cutter constructed and arranged to support a truing tool. 100

3. In a machine of the class described, a shaft, carrying a cutter, and a stationary sleeve encircling the shaft having a guard for the cutter while leaving substantially the entire periphery of the cutter exposed, and a rest having a surface substantially parallel to the axis and opposite the face of the cutter to support a truing tool. 105

4. In a machine of the class described, a shaft adapted for high-speed rotation carrying a cutter, and a stationary sleeve encircling the shaft having a guard for the cutter and a rest for a truing tool, the sleeve being adjustable around the shaft whereby the rest may be placed in inoperative position. 110

5. In a machine of the class described, a shaft adapted for high-speed rotation carrying a cutter, a stationary sleeve encircling the shaft and having its end constructed 120 and arranged to act as a guard for preventing the operator's hand from coming into contact with a side of the cutter while leaving substantially the entire periphery of the cutter exposed, and a steady rest projecting 125 from said sleeve, substantially parallel to the axis of and opposite the face of the cutter to act as a support for a truing tool.

6. In a machine of the class described, a shaft adapted for high-speed rotation carrying a cutter, a stationary sleeve encircling the shaft and having its end constructed and 5 arranged to act as a guard for the cutter, and a steady rest projecting from said sleeve, the sleeve being adjustable around the shaft

to place the rest in operative or inoperative position, but the guard being in operative position at all times.

In testimony whereof I have signed my name to this specification.

HARRY T. BLACKWELL.
